UNITED STATES PATENT OFFICE

2,300,116

GLIDER CONSTRUCTION

Aaron S. Goldberg, Philadelphia, Pa., assignor to
 Bunting Glider Company, Philadelphia, Pa., a
 corporation of Pennsylvania

Application April 5, 1941, Serial No. 387,043

3 Claims. (Cl. 155—194)

This invention relates to gliders and more particularly to an improved construction of all-metal glider, it being among the principal objects of the present invention to produce a glider having a minimum number of parts which are adapted to be readily assembled and disassembled without the use of any specially designed tools and which is relatively inexpensive and simple to manufacture, strong in construction, durable and comfortable in use and neat in appearance.

The present invention consists substantially in the combination, construction, location and relative arrangement of parts, all as will be described more fully hereinafter, as shown in the accompanying drawing and as finally pointed out in the appended claims. In the said accompanying drawing:

Figure 1 is a front perspective view of a glider constructed in accordance with and embodying the principles of the present invention;

Figure 2 is a front perspective view showing the several parts of the glider in separated relation;

Figure 3 is a rear perspective view of the glider in partially assembled condition;

Figure 4 is a partial perspective view showing the assembled seat, back and side arm panels in relation to one of the supporting hangers therefor;

Figure 5 is a transverse vertical sectional view taken on the line 5—5 of Figure 1;

Figure 6 is a rear perspective view of the portion inscribed within the dotted circle of Figure 3; and

Figure 7 is a view of one of the anchoring bolts employed for securing the seat and back panels to the side arm panels.

Referring now more particularly to the drawing, it will be observed that the glider of the present invention is of the type having seat, back and side arm parts adapted to be removably secured together to provide a unitary assembly which is swingably suspended between a pair of laterally spaced end supporting frames 10—10 of any suitable type and construction, examples of such end frames being shown in applicant's prior United States Letters Patent Nos. 1,997,054 and 2,210,076. As shown in these prior patents, the end frames 10—10 are suitably interconnected and braced by means not herein shown to provide a rigid supporting structure for the swinging seat and back unit, the latter being suspended by means of the strap hangers 11, the upper ends of which are pivotally connected to the upper rails 12—12 of the end frames.

Except as they may be modified as hereinafter pointed out, the glider of the present invention includes a pair of side arm panels 13—13 which are similar in all substantial respects to those shown in applicant's prior United States Letters Patent No. 2,177,616, each of these panels having secured to their front and rear vertical edges the reinforcing straps 14 and 15. The lower ends of these straps are formed into semi-circular outline to provide in effect outwardly-turned J-shaped lower extremities to which are pivotally connected the lower ends of the suspension straps or hangers 11. Thus, through the intervention of the side arm panels 13—13, the entire weight 15 of the swinging seat and back unit is suspended from the hangers 11, the said unit being free to glide back and forth between the supporting end frames 10—10. The upper portions of the side panels 13—13 are each outwardly turned, as at 20 13a—13a, to provide arm rests and protective guards above the stationary supporting end frames.

Heretofore and prior to this invention, gliders have been constructed in which the parts hereinbefore described have been employed. However, in such prior constructions of glider the conventional practice has been to employ upholstered spring seat units or spring-fitted frames upon which removable cushions have been placed.

30 The glider of the present invention dispenses with such spring-fitted seats and instead employs a sheet-metal seat unit 16 produced in the form of a single stamping having a main seat portion 16a and a depending apron extending longitudinally along the frontal edge thereof. Preferably, the seat portion 16a is curved from front to rear and the frontal edge thereof is rounded to merge with the depending apron 17 to provide a comfortable seat for the occupant of the glider. To strengthen the seat unit 16 and to provide it with adequate rigidity, the rear surface thereof has welded or otherwise secured thereto a plurality of laterally spaced reinforcing bands 18, the rear extremities 19 of which project freely 40 beyond the rear longitudinal edge of the seat unit 16 for a purpose which will be presently apparent. Preferably, the rear longitudinal edge of the sheet metal panel forming the seat unit is reversely bent upon itself to provide a neat and smooth rear edge for the seat unit.

45 The back unit 20 of the glider is similarly formed of a single sheet metal stamping the upper edge of which is rolled, as at 21, to provide a smooth finished edge. As in the case of the seat unit 16, the back panel is also reinforced and

rigidified with a plurality of laterally spaced bands 22, these being laterally spaced in correspondence with the spacing of the reinforcing for the seat unit 16. Also, the lower ends of the bands 22 project freely beyond the bottom longitudinal edge of the back panel and are rearwardly bent, as at 23, at such angle that when the seat and back units 15 and 20 are properly assembled the extremities 23 of the bands 22 respectively make flat contact with the corresponding extremities 19 of the bands 18. In this connection, it will be noted that the band extremities 19 and the band extremities 23 are respectively provided with registering apertures 24 and 25.

As most clearly appears in Figure 2, the seat panel 16 is provided at each of its opposite ends with a pair of bolts 26—26 of the character shown in detail in Figure 7, each pair of these bolts being secured in vertically spaced relation to the depending apron 17 of the seat unit. As quite clearly appears in Figure 7, each of these anchoring bolts 26 is provided with a flat body portion 27 which is integral with the threaded shank 28 of the bolt, this shank being adapted to threadedly receive a cap nut 29. The body portion 27 of the bolt is provided with an aperture 30 therein through which a rivet or other securing device may be projected for permanent securement of the bolt to the seat panel as shown in Figure 2, it being observed that the threaded shanks 28 of the bolts project freely beyond the opposite vertical edges of the seat unit apron 17 to which the bolts are secured. A pair of vertically spaced apertures 31 are provided in each front reinforced edge of the side arm units 13—13 through which the shanks of the bolts 26 project.

In similar fashion, the back panel 20 of the glider is provided at opposite side edges thereof with anchoring bolts 32—32 which are similar in all respects to the anchoring bolts 26, these bolts 32—32 being respectively adapted for projection through suitable apertures 33 provided in the rear reinforced edges of the side arm panels.

In order to assemble the swinging unit of the glider, which includes the seat, back and side arm panels, the seat and back panels 16 and 20 are first connected together by means of bolts 34 which are projected through the registering apertures 24 and 25 of the aligned reinforcing bands 18 and 22. The oppositely projecting threaded shanks of the bolts 32 are then projected through the apertures 33—33 of the side arm panel units 13—13 while the threaded shanks of the front bolts 26—26 are projected through the apertures 31 of the side arm units, the latter units being then secured in place by the cap nuts 29 which are respectively threaded onto the anchoring bolts. The arrangement and fit of the several parts is such that the side arm panels are respectively drawn tightly against the opposite side edges of the seat unit to form a neat joint therewith at the same time that the front apron 17 of the side unit is disposed substantially flush with the front vertical edges of the side arm panel units. The assembled seat and back panels are thus firmly secured in place and supported between the side arm panels solely by the anchoring bolts 32—32 at the rear thereof and by the anchoring bolts 26—26 at the front thereof.

In order to preclude any tendency for the side arm panels to skew out of parallel relation, a

spacer rod 35 is interposed between the freely extending bottom portions of the rear reinforcing straps 15—15 of the side arm panel units. Preferably, this spacer rod 35 is interiorly threaded at its opposite ends for reception of bolts 36—36 which are projected through suitable apertures 37 provided in said straps 15—15. This spacer rod 35, conjointly with the anchoring bolts 32 and 26, serve to brace the side arm panels firmly against the opposite side edges of the seat and back assembly and so provides for an exceedingly rigid swinging unit, which unit is adapted to be suspended by means of the strap hangers 11 between the stationary end frames 10—10.

5 It will be understood, of course, that the invention is susceptible of various changes and modifications from time to time without departing from the real spirit or general principles thereof and it is, accordingly, intended to claim 10 the same broadly, as well as specifically, as indicated by the appended claims.

20 What is claimed as new and useful is:

1. An all-metal glider assembly adapted to be 25 swingably suspended between a pair of vertical end units arranged in laterally spaced substantially parallel relation and rigidly connected together comprising individually fabricated seat, back and side arm units each formed of a single sheet metal panel, a plurality of laterally spaced 30 parallel reinforcing bands extending from edge to edge of each said seat and back panels, the bands of said seat panel being respectively in longitudinal alignment with the bands of said back panel with the proximate ends of said bands 35 extending freely with respect to their associated panels, the freely extending ends of each aligned pair of said bands being angularly related for flatwise engagement with each other and being provided with registering apertures, securing 40 means projected through said registering apertures for securing together said engaging ends of the bands, and means for detachably securing said arm units to the assembled seat and back units.

45 2. An all-metal glider assembly adapted to be swingably suspended between a pair of vertical end units arranged in laterally spaced substantially parallel relation and rigidly connected together comprising seat, back and side arm units 50 each formed of a single sheet metal panel, the seat and back units being adapted for assembly with the rear longitudinal edge of the seat unit in close proximity to the bottom longitudinal edge of the back unit, each of said seat and back units 55 being provided with a plurality of laterally spaced securing elements extending freely beyond the said longitudinal edges of said units, the securing elements of one unit being spaced for registry with the securing elements of the other unit, means for detachably connecting together each 60 pair of registering securing elements, and means for detachably securing said side arm units to the assembled seat and back units.

3. An all-metal glider assembly of the character defined in claim 2 wherein said securing elements are formed as free extensions of laterally spaced rigidifying members permanently secured to and extending transversely of each of said seat and back units.

AARON S. GOLDBERG.
